ILLINOIS.

STENCIL ADDRESSING-MACHINE.

1,272,926.

Specification of Letters Patent. Patented July 16, 1918.

Application filed September 30, 1915. Serial No. 53,285.

To all whom it may concern:

Be it known that we, JOSEPH S. DUNCAN and ULYSSES G. LEE, citizens of the United States, both residing at Chicago, in the county of Cook and State of Illinois, have jointly invented certain new and useful Improvements in Stencil Addressing-Machines, of which the following is a specification.

This invention relates to printing machines and more particularly to a machine for printing addresses and information of a similar character from stencils.

Machines of this general character heretofore suggested or used have been subject to several disadvantages, among which are the failure to distribute the ink uniformly to the stencil with the result that distinct and even impressions are not obtained in every instance. A further disadvantage arises from the inability of earlier machines to automatically repeat the impression as is frequently desirable, as where a list of impressions taken is required for record.

It is an object of our invention to overcome the imperfections and disadvantages of machines heretofore known or in use for this purpose by the provision of means whereby uniform application of the ink to the stencil is assured in every instance. A further object of our invention is the provision of a machine of simple and inexpensive construction whereby the operator by a simple adjustment is enabled to obtain one or more impressions from individual stencils without the necessity of manipulating the stencils.

Other objects and advantages of our invention will be apparent as it is better understood by reference to the following specification when read in connection with the accompanying drawing illustrating the preferred embodiment thereof in which—

Figure 1 is a plan view of the machine according to our invention;

Fig. 2 is a side elevation thereof;

Fig. 3 is a vertical section on the line 3—3 of Fig. 1;

Fig. 4 is a vertical section on the line 4—4 of Fig. 1;

Fig. 5 is a detail plan view of the stencil guideway and the means for moving the stencils;

Figs. 6, 7 and 8 are detail plan views of the repeating mechanism;

Fig. 9 is a detail sectional view of the 55 repeating selector,

Fig. 10 is a detail in elevation of the inking roller actuating mechanism, and

Fig. 11 is a section on the line 11—11 of Fig. 6.

Referring to the drawings, 1 indicates a base of suitable form and construction to support the various parts of the mechanism as hereafter described. Pivoted thereto on the base 1 is an operating arm 3 provided with a handle 4, whereby the arm 3 may be swung about its pivot 2, the movement being, however, limited by the engagement of a lug 5 on an extension 6 of the arm 3 with the lugs 7 and 8 on the base 1. A link 9 is pivotally secured at 10 to the operating arm 3 and a bifurcated extension 43 thereof embraces the shaft 26 (Fig. 4). The link 9 is provided at its opposite end with a pivoted pawl 11 normally forced outwardly by a spring 12. The pawl 11 is adapted to engage a tooth 13 formed on the end of the bell-crank lever 14, pivotally mounted at 15 on the base 1, the bell-crank lever 14 being normally held 80 in the position indicated in Fig. 1 by a spring 16 secured thereto at 17 and to the base 1 at 18. The bell-crank lever 14 is bifurcated at its opposite end, forming arms 19 between which is disposed a cylindrical 85 member 20 rigidly secured to the pin 21 forming a pivot for the toggle links 22 and 23. The link 22 is pivotally connected by means of a pin 24 to the inking roller supporting arm 25. The arm 25 is pivotally mounted on a shaft 26 and, as will be readily understood, when the toggle formed by the links 22 and 23 is straightened the arm 25 will be moved about its pivot. A spring 25', secured to the arm 25 at 23' and to the 95 base 1 at 26', normally maintains the arm 25 in its uppermost position.

Referring particularly to Figs. 3 and 4, the toggle link 23 is pivotally connected at 27 with the platen arm 28 extending transversely of the machine and rotatably mounted on the shaft 29. The platen arm 28 is provided with a platen 29' which is normally disposed in the position indicated in Fig. 3,

being held in this position by a spring 30 secured at 31 to the platen arm 28 and to the base 1 at 32. A stop 33 is secured to the base 1 and provided with a buffer 34 of 5 felt or other suitable material to lessen the force of the blow and reduce the amount of noise as the platen arm 28 is forcibly returned to its normal position after the printing operation, it being understood from the 10 foregoing that when the toggle is straightened the platen 29' will move upwardly into printing position to support the impression-receiving material.

In order that the arm 25 and the platen 15 29' may be sustained in the printing position during the printing operation a dog 35 (see Fig. 1) is pivotally mounted at 36 on the base 1 and is adapted to engage a lug 37 on the bell-crank lever 14 and therefore 20 by hold the toggle in straightened position until the bell-crank lever 14 is released after the close of the printing operation. A spring 38, secured to the base 1 at 39 and to the dog 35 at 40, normally urges the dog 25 in the direction of the lug 37. The dog 35 is provided with a tail 41 disposed in the path of a roller 42 carried by the extension 43 of the link 9 and, as will be readily understood, when the link 9 is moved by 30 means of the operating arm 3 into position to allow the roller 42 to engage the tail 41 the dog 35 will release the bell-crank lever 14, allowing springs 16, 25' and 30 to break the toggle with the result that the inking- 35 roller supporting arm 25 and the platen arm 28 return to normal position.

The inking-roller supporting arm 25 is provided at its extremity with a pair of tracks or guideways 44 (see Fig. 3) upon 40 which a frame 45, carrying the inking mechanism, is slidably supported. The inking mechanism comprises an inking roller 46 having a smooth resilient surface of any suitable material such for example as the 45 composition used in ordinary printers' inking rollers. The inking roller 46 is mounted on a shaft 47, which is suitably journaled at either end in the frame 45. A gear 48 is secured to the shaft 47 and meshes 50 with a pinion 49 secured to the shaft 50 to which is also secured a gear 51 which meshes with a rack 52 formed on the underside of the arm 25 adjacent one of the guideways 44. An ink supplying roller 53 is pivotally 55 mounted in the arms 54 (Fig. 2) secured to the frame 45 by screws 54' (Fig. 10). The roller 53 is provided with a surface of felt or other absorbent material which may be saturated with ink and inasmuch as the 60 roller 53 is disposed in engagement and rotates with the inking roller 46 a sufficient quantity of ink will be transferred to the inking roller 46 at each printing operation. The roller 46 is maintained in proper relation to the printing position by means of 65

spacing wheels 55 secured to the shaft 47, which are in turn engaged by the spacing wheels 56 rotatably mounted on the side members of the frame 45 and rolling on the undersides of the tracks 44. The frame 45 70 is connected by means of a link 57 (see Fig. 1) with an extension 58 of the link 9 and as the link 9 is reciprocated the inking roller 46 will be moved longitudinally of the machine while at the same time, as previously explained, the inking-roller supporting arm 25 will turn about its pivot to carry the inking roller 46 downwardly into printing position.

A magazine 59 is disposed at one end of 80 the bed 1 adjacent the printing position and is adapted to hold a plurality of stencils 60, a weight 61 being provided to maintain the requisite degree of pressure on the stencils 60 within the magazine. A pair of 85 grooved guideways 62 are secured to the bed 1 in the plane of the bottom of magazine 59 and are adapted to support the stencils 60 during and following the printing operation, the stencils being guided thereby to a 90 position at the opposite end of the machine where they fall into a receiving magazine 63 disposed beneath the plane of the guideways 62. To move the stencils 60 from the magazine 59 along the guideways 62 I provide a member 64 slidably mounted in grooves formed in extensions of the guideways 62 and provided with projecting noses 65 adapted to pass beneath the lowermost stencil in the magazine 59 and to engage 95 the edge thereof whereupon the stencil 60 is forced from the magazine 59 in the subsequent operation of the machine and moved along the guideways 62 into printing position. The actuation of the member 64 is 100 accomplished through a bar 66 rigidly secured thereto and provided with a shoulder 67 adapted to be engaged by a pawl 68 pivotally mounted at 69 near the end of the link 9. A spring 70, secured to the link 9 110 at 71 and to the pawl 68 at 72 normally maintains the pawl 68 in position to engage the shoulder 67. Movement of the link 9 to the right viewing Fig. 5 is thus transmitted to the bar 66. A pin 99 near the end 115 of the bar 66 engages a notch in the end of the link 9 so that the bar 66 is moved to the left, viewing Fig. 5 with the link 9. The pin 99, however, permits movement of the link 9 to the right viewing Fig. 5 independently of the bar 66 when the pawl 68 is disengaged from the shoulder 67.

As previously pointed out it is sometimes desirable that the stencils remain in printing position during two or more operations 125 of the machine in order that a plurality of impressions may be obtained from the stencils. I have accordingly provided the pawl 68 with an upstanding pin 73, whereby the pawl 68 may, through coöperation of the 130

pin 73 with the mechanism about to be described, be selectively held from engagement with the shoulder 67 or allowed to engage therewith to attain the desired result.

5 An upstanding pin 74 is rigidly secured to the end of the link 9. Loosely mounted on the pin 74 is a selector member comprising a cam 75 (see Fig. 9) having oppositely disposed arms 76, an upstanding cylindrical portion 77 and a knurled head 78. Journaled on the portion 77 is a second cam 79 having a plurality of teeth 80, the alternate depressions between the teeth 80 being of different depth. A pin 81 is secured to the 10 underside of the cam 75 and is adapted to be disposed in one or the other of the openings 82 and 83 in the end of link 9. The opening 82 does not pass entirely through the link 9 and when the pin 81 is 15 disposed therein the cam 79 is raised sufficiently to clear the end of the pin 73 (Fig. 4), and the arms 76 of the cam 75 are so disposed that they can not engage the pin 73. The pawl 68, is, therefore, not affected by 20 the selector and actuates the bar 66 following each printing operation to dispose a fresh stencil in printing position.

The opening 83 is of sufficient depth to allow the selector to drop to a position in 25 which the pin 73 is in the path of the teeth 80 of the cam 79. A pawl 84 is pivotally mounted at 85 on the base 1 and is normally held by a spring 86 in position to engage the teeth of the cam 79 as the link 9 reciprocates. In Fig. 7 of the drawing we have 30 illustrated the pin 73 disposed in a depression of lesser depth between the teeth 80 of the cam 79, the pawl 68 being thereby held from engagement with the shoulder 67 of the bar 66. At the next succeeding operation 35 of the machine the pawl 84 will engage one of the teeth 80 of the cam 79 and rotate it so that the pin 73 will be disposed in the following and deeper depression between the 40 teeth 80, allowing the pawl 68 to engage the shoulder 67 and actuate the bar 66. It will be understood, therefore, that the connection between the link 9 and the bar 66 is alternately made and broken and that, therefore, 45 the member 64 will cause the advance of a stencil from the magazine at each alternate actuation of the machine. Each of the stencils 60 will, therefore, remain in printing position during two printing operations so that 50 55 duplicate impressions may be made.

In order that more than two impressions may be made, if desired, we provide the cam 75, as illustrated in Fig. 8, with a projecting portion 87 of sufficient height to hold the 60 pawl 68 from engagement with the shoulder 67 of the bar 66 when the portion 87 is so disposed as to engage the pin 73. A shallow opening 88 is provided in the end of the link 9 which, when engaged by the pin 65 81 on the cam 75, maintains the projecting

portion 87 of the cam 75 in the desired position of the parts. In this position the pawl 68 is held from engagement with the shoulder 67 on the bar 66, hence the member 64 will not be actuated while this adjustment 70 is maintained and the particular stencil which is disposed in printing position will remain in this position until the desired number of impressions have been taken and the adjustment is changed to successively 75 feed stencils from the magazine.

The operation of the machine should be apparent from the foregoing without further description of the structure. Viewing Fig. 1 at the beginning of the movement 80 of the operating arm 3 to the right the pawl 11 through its engagement with the bell-crank lever 14 causes the toggle, consisting of the links 22 and 23 to straighten, moving the printing-roller supporting arm 25 about 85 its pivot until the inking roller 46 engages the stencil disposed in printing position. Simultaneously the platen 29' is moved upwardly to support the impression receiving material beneath the stencil. The dog 35 90 immediately engages the abutment 37, the hook on the former passing behind the latter to maintain the parts in printing position against the tensioned spring 16 during the remainder of the printing stroke, during 95 which the inking roller 46 is revolved by the engagement of the gear 51 with the stationary rack 52. The rolling pressure accompanied by sufficient ink to produce the impression is transferred thereby to the stencil. 100 Near the end of the stroke to the right the roller 42 engages the tail 41 of the dog 35 and releases the toggle as previously explained, whereupon the inking roller supporting arm 25 and the platen 29' are re- 105 turned to normal position.

Meanwhile, if the selector is adjusted to feed stencils successively after each printing operation the member 64 has been moved to the extreme right, viewing Fig. 5, through 110 engagement of pawl 68 with shoulder 67 of bar 66 and the noses 65 on the member 64 pass the edge of the lowermost stencil 60 and upon the return movement of the operating arm 3 the bar 66, through engagement of the link 9 with the pin 99, is actuated to carry a fresh stencil to printing position. If the duplicating or repeating 115 adjustments have been made the member 64 will operate in the manner previously described to dispose a fresh stencil in printing position at each alternate operation of the operating arm 3 or to prevent feeding of the stencils until the adjustment is changed.

From the foregoing description it will be 125 apparent that we have succeeded in perfecting a stencil printing machine in which not only is a substantially uniform ink supply assured throughout the printing operation but also the operator is enabled, by a simple 130

adjustment and without manipulating the stencils, to obtain one or more impressions from the individual stencils as desired. It will be further understood that the machine 5 involves a minimum number of simple and inexpensive parts, that it has no complicated mechanism which is liable to derangement and that it will perform the desired operations rapidly and efficiently.

- 10 It will be apparent that various changes may be made in the form, construction and arrangement of the parts without departing from the spirit and scope of the invention, or sacrificing any of its material advantages, the form hereinbefore described being 15 merely a preferred embodiment thereof.

We claim:

1. In a stencil printing machine, the combination of a bed, pivoted arms supporting 20 respectively a platen and a bodily movable inking roller carriage, inking and ink-supplying rollers journaled in said carriage, means for actuating said arms to move said platen and carriage oppositely toward and 25 from said bed, means for reciprocating said carriage relatively to its supporting arm, and means for advancing stencils along said bed to printing position between said platen and carriage.

- 30 2. In a stencil printing machine, the combination of a bed, pivoted arms supporting respectively a platen and a bodily movable inking roller carriage, inking and ink-supplying rollers journaled in said carriage, a 35 toggle connecting said arms, means for actuating said toggle to swing said arms and thereby move said platen and carriage oppositely toward and from said bed, means for reciprocating said carriage relatively to 40 its supporting arm, and means for advancing stencils along said bed.

3. In a stencil printing machine, the combination of a bed, pivoted arms supporting 45 respectively a platen and a bodily movable inking roller carriage, an inking roller journaled in said carriage, a toggle connecting said arms, a bell-crank lever connected to said toggle, a reciprocable member having means for engaging one arm of said bell- 50 crank lever, means for actuating said reciprocable member whereby said toggle is straightened to swing said arms and move said platen and carriage oppositely toward said bed, a connection between said reciprocable member and carriage for reciprocating the latter relatively to its supporting arm, and means for advancing stencils along said bed.

- 60 4. In a stencil printing machine, the combination of a bed, pivoted arms supporting respectively a platen and a bodily movable inking roller carriage, an inking roller journaled in said carriage, a toggle connecting said arms, a bell-crank lever connected to 65 said toggle, a reciprocable member having

means for engaging one arm of said bell-crank lever, means for actuating said reciprocable member whereby said toggle is straightened to swing said arms and move said platen and carriage oppositely toward 70 said bed, a connection between said reciprocable member and carriage for reciprocating the latter relatively to its supporting arm, means for advancing stencils along said bed, and an automatically controllable connection between said reciprocable member and last-mentioned means.

5. In a stencil printing machine, the combination of a bed, pivoted arms supporting respectively a platen and a bodily movable 80 inking roller carriage, inking and ink-supplying rollers journaled in said carriage, means for actuating said arms to move said platen and carriage oppositely toward and from said bed, means for reciprocating said 85 carriage relatively to its supporting arm, means for advancing stencils along said bed to printing position between said platen and carriage, and automatic means for controlling said advancing means.

6. In a stencil printing machine, the combination of a bed, pivoted arms supporting respectively a platen and a bodily movable inking roller carriage, inking and ink-supplying rollers journaled in said carriage, 95 means, including a reciprocable member, for actuating said arms to move said platen and carriage oppositely toward said bed, a link connecting said reciprocable member and carriage, and means for advancing stencils 100 along said bed.

7. In a stencil printing machine, the combination of a bed, pivoted arms supporting respectively a platen and a bodily movable inking roller carriage, inking and ink-supplying rollers journaled in said carriage, means, including a reciprocable member, for actuating said arms to move said platen and carriage oppositely toward said bed, a link connecting said reciprocable member and carriage, means for advancing stencils along 110 said bed, and an automatically controllable connection between said reciprocable member and last-mentioned means.

8. In a stencil printing machine, the combination of a bed, pivoted arms supporting respectively a platen and a bodily movable inking roller carriage, actuating means for swinging said arms to move said platen and carriage oppositely toward said bed, means for temporarily locking said arms with said platen and carriage in coöperating relation, a connection between said actuating means and carriage whereby the latter is moved longitudinally of said bed, and means for advancing stencils along said bed.

9. In a stencil printing machine, the combination of a bed, pivoted arms supporting respectively a platen and a bodily movable inking roller carriage, actuating means for 120

swinging said arms to move said platen and carriage oppositely toward said bed, means for temporarily locking said arms with said platen and carriage in coöperating relation, 5 a connection between said actuating means and carriage whereby the latter is moved longitudinally of said bed, means for automatically releasing said locking means when said carriage has completed its forward 10 stroke, and means for advancing stencils along said bed.

10. In a stencil printing machine, the combination of a bed, pivoted arms supporting respectively a platen and a bodily movable inking roller carriage, actuating means for swinging said arms to move said platen and carriage oppositely toward said bed, means for temporarily locking said arms with said platen and carriage in coöperating 15 relation, a connection between said actuating means and carriage whereby the latter is moved longitudinally of said bed, means for automatically releasing said locking means when said carriage has completed its forward 20 stroke, means for advancing stencils along said bed, and an automatically controllable connection between said actuating and last-mentioned means.

11. In a stencil printing machine, the 30 combination of a bed, pivoted arms supporting respectively a platen and a bodily movable inking roller carriage, actuating means for swinging said arms to move said platen and carriage oppositely toward said bed, a 35 spring-pressed latch to hold said arms with said platen and carriage in coöperating relation, a connection between said actuating means and carriage, whereby the latter is moved longitudinally of said bed, and means for advancing stencils along said bed.

12. In a stencil printing machine, the combination of a bed, pivoted arms supporting respectively a platen and a bodily movable inking roller carriage, actuating means 45 for swinging said arms to move said platen and carriage oppositely toward said bed, a spring-pressed latch to hold said arms with said platen and carriage in coöperating relation, a connection between said actuating 50 means and carriage, whereby the latter is moved longitudinally of said bed, means for automatically releasing said latch when said

carriage has completed its forward stroke, and means for advancing stencils along said bed.

55

13. In a stencil printing machine, the combination of a bed, pivoted arms supporting respectively a platen and a bodily movable inking roller carriage, actuating means for swinging said arms to move said platen 60 and carriage oppositely toward said bed, a spring-pressed latch to hold said arms with said platen and carriage in coöperating relation, a connection between said actuating means and carriage, whereby the latter is 65 moved longitudinally of said bed, means for automatically releasing said latch when said carriage has completed its forward stroke, means for advancing stencils along said bed, and an automatically controllable connection 70 between said actuating and last-mentioned means.

14. In a stencil printing machine, the combination of a bed, pivoted arms supporting respectively a platen and a pair of guiding tracks, a frame supported on said tracks, an inking roller journaled in said frame, a rack adjacent one of said guiding tracks, an operative connection between said rack and inking roller, and actuating means for 80 swinging said arms to move said platen and tracks oppositely toward said bed and to move said frame along said tracks.

15. In a stencil printing machine, the combination of a bed, pivoted arms supporting respectively a platen and a pair of guiding tracks, a frame supported on said tracks, an inking roller journaled in said frame, a rack adjacent one of said guiding tracks, an operative connection between said 90 rack and inking roller, actuating means for swinging said arms to move said platen and tracks oppositely toward said bed and to move said frame along said tracks, grooved spacing wheels mounted concentrically with 95 said inking roller, and flanged spacing wheels between said grooved spacing wheels and tracks.
